UNITED STATES PATENT OFFICE.

PHILIP N. SEA, OF CHICAGO, ILLINOIS.

CALCULATING-MACHINE.

1,247,730.

Specification of Letters Patent. Patented Nov. 27, 1917.

Application filed November 20, 1916. Serial No. 132,294.

To all whom it may concern:

Be it known that I, PHILIP N. SEA, a citizen of the United States, and a resident of Chicago, in the county of Cook and State 5 of Illinois, have invented certain new and useful Improvements in Calculating-Machines, of which the following is a specification.

My invention relates to calculating machines particularly to that class in which, by means of a key-board, printing type members are selected for operation, and are then by means of manual or power controlled actuating mechanism operated to print on a 10 record sheet, the invention covering improved means by which the operator may readily determine before printing actually takes place just what is going to be printed.

In calculating machines such as the "Burroughs", eighty-one numeral keys are usually provided and these keys remain depressed after a setting operation so that the operator may check up the entry before printing. Registers are also visible for indicating 15 cumulating totals, so that in these machines the operator can readily check up before printing. There are, however, other types of machines in which no provision is made for such indication or observation. Examples of such machines are the "Dalton" and "Sundstrand" machines which have been used for many years throughout the country. In machines of this type there are only ten 20 numeral keys, and these keys do not stay down after a setting-up depression thereof, and the calculating registers are well within 25 the body of the machine and cannot be seen by the operator, no means being therefore provided for determining before printing 30 just what is going to be printed and there is therefore no positive checking means.

The object of my invention is therefore to provide simple means whereby the operator may at any time determine before actual 35 printing on the record sheet what has been set up on the machine for printing, or what totals the registers contain. In machines of the "Dalton" and "Sundstrand" type, decimal order sectors or frames are provided 40 which are movable vertically or substantially so and each of which carries a vertical row of horizontally shiftable printing bars, usually ten in number, for printing numerals ranging from 0 to 9. By means of the 45 key-board such type frames or sectors are selected and their degree of movement estab-

lished, and actuating mechanism controlled manually or by power is operated after manipulation of the key-board to raise the selected type sectors or frames to bring the 50 corresponding type bars into a printing line, whereupon striking mechanism is released to strike such type bars to effect printing pressure of the bars on a record sheet. The front ends of the type bars either at or above 55 the striking line are always visible to the operator or can be readily made so, and I take advantage of this fact, my invention being the application of indicating numerals 60 at the front ends of the type bars in such 65 position that after manipulation of the numeral keys, or total, sub-total or other auxiliary keys, and before striking of the type bars, the indicating numerals will be arranged in a sight line in accordance with 70 the key-board set-up so that the operator may determine just exactly what is going to be printed on the record sheet before the machine is operated to print. The invention can be reduced to practical form in a 75 number of ways, and on the accompanying drawings I show an application thereof. In these drawings

Figure 1 is a front elevational view of a machine of the "Dalton" type, 85

Fig. 2 is a side elevational view with part of the inclosing housing in section and part of the apparatus supporting frame removed,

Fig. 3 is a top view of one of the type bars 90 showing a modified way of applying indicating characters,

Fig. 4 is a top view of one of the type bars showing another way of applying indicating characters, and 95

Figs. 5 and 6 are side and front views respectively of the upper end of one of the top sectors showing another modified way of applying indicating characters at the front ends of the type bars. 100

As in machines of the class shown the operation is well understood in the art, it is unnecessary to show all of the intricate operating and coöperating parts and I have therefore shown only such parts as will 105 clearly illustrate the adaptation and operation of my invention. Referring to the drawings, 10 represents the supporting base of the machine, 11 the frame-work for supporting the operating parts, and 12 the inclosing housing. On the shaft 13 the type sectors 14 are pivoted, each of which at its 110

outer end carries a frame 15 in which is accommodated a vertical row of type bars 16, these type bars being shiftable transversely and normally held in front position 5 by springs 17. In the machine housing the slot 18 is provided through which the front ends of the type sectors may pass during operation of the machine, to be brought in front of the type roller 19 mounted on the 10 housing and having associated therewith the usual mechanism 20 for propelling the record sheet or band 21 between the roller and the type bars. Inking ribbon, not shown, is fed from ribbon spools within holders 22 in 15 a manner well understood in the art. Pivoted also on the shaft 13 are sector gears 23 which mesh with pinions 24 controlled by the registers or totalizers (not shown). Springs 25 between the type sector and the 20 frame-work 11 and the springs 26 between the type sector and the sector gears tend to swing the type sectors upwardly, but normally such swing is prevented by the engagement with the rear edge of slots 27 in the 25 type sectors by pins 28 on the sector gears. The machine has ten numeral keys 29 and auxiliary keys such as a correction key 30, a repeat key 31, a total key 32, a combination key 33, and a designating key 34, the 30 functions of such auxiliary keys being well understood. Numbers desired to be printed in the machine are set up by the numeral keys and then the machine lever 35 is swung forwardly to rotate the corresponding pinions 24 and to swing the corresponding sector gears 23 through arcs depending upon the set-up, and the distance that these gear sectors swing forwardly determines the distance that the type sectors swing upwardly, 35 40 the type bars of the various decimal order type sectors corresponding with the set-up being then arranged in a horizontal printing plane ρ ready to be struck by the hammers 36 which are released from the triggers 37 45 during further movement of the operating lever 35. The rear ends of the type bars have the raised printing numerals 38 thereon and when these bars are struck by the hammers they press the inking ribbon against the 50 record sheet and print the entry. After return of the operating lever 35 to normal position the hammers, type sectors, sector gears and other parts of the machine are restored to normal position, the type roller being advanced to shift the paper upwardly for the 55 printing of the next entry.

In machines of the type of construction just described there is nothing which will enable the operator to ascertain, before actual 60 printing, just what is going to be printed. For example, after a set-up on the machine he has no means of ascertaining whether the set-up is correct. In machines of the "Burroughs" type the keys remain depressed 65 after setting up depression thereof, and

from the depressed keys the operator can check up on the set up, but in machines of the "Dalton" and other types the keys do not remain depressed during a set-up operation. Furthermore, in such machines the 70 registers or accumulators are not visible, and other indicating registers are not provided so that the operator is unable to ascertain sub-totals, totals, or other information before printing on the record sheet. The 75 printing type characters are also invisible to the operator as they are at the rear ends of the type bars. The front ends of raised type sectors and the front ends of the type bars thereon are, however, visible to the 80 operator or can be readily made so, and on this fact my invention is based, and I therefore place at the front ends of the type bars characters which are indicative of the printing characters on the rear ends of the type 85 bars so that by observing the indicating characters at the front ends of the type bars the operator can determine positively what is going to be printed. On some machines of the type described a cover 39 is provided 90 for protecting the hammers 36 and in other machines such cover is omitted. Where the cover is omitted the front end of each type bar may have applied thereto a character which is the same as the printing character 95 at the rear end of the bar, and then when the type sectors are raised after a set-up operation and before the hammers are actuated, the indicating characters at the front ends of selected type bars will all be in the 100 printing plane ρ and the item which is to be printed can be readily determined by the operator. If the entry is correct the machine is further actuated to release the hammers to effect printing, and if a mistake has been 105 made the correction key can be depressed and the correct set-up made. However, where a cover is provided for the hammers it may be more desirable to have the indicating plane above the printing plane in 110 order that the indicating characters may be more readily seen. In the drawings I have shown the indicating plane α one step above the striking or printing plane and the indicating numbers on the type bars are therefore off-set upwardly one unit from the printing characters on the bar, that is, the "0" printing type bar has the indicating numeral "1" at its front end, the "1" printing type bar has the indicating numeral "2" 115 at its front end, and so on, and the "0" indicating numeral may be omitted or applied to the front of the type sectors above the zero printing bar, or projections 40 may be provided at the tops of the type sectors in 120 line with the type bars to receive the "0" numeral indication. The front edge 41 of the cover 39 is preferably beveled down so that the indicating characters in the indicating plane α — α are clearly visible to the 125 130

operator. In the drawings the set-up on the machine and on the type sectors is the number 345,482,457. In the printing plane $p-p$ this number is formulated by the 5 printing characters on the inner ends of the type bars in the printing plane, and in the indicating plane $x-x$ this number appears on the front ends of the row of type bars above those in the printing plane, and the 10 operator observing the numbers in the indicating plane knows whether or not the set-up is correct. If correct, he operates the machine to release the hammers to strike the front ends of the bars in the printing 15 plane to effect printing on the record sheet. If the set-up is wrong, the entry can be destroyed and corrections made. If the operator desires to ascertain the reading of the registers or accumulators in the machine he 20 depresses the proper auxiliary key and actuates the operating lever to bring the type sectors into position, then by reading the indication in the plane $x-x$ he can get the desired information.

25 It is evident that instead of offsetting the indicating numerals one step, as shown, they may be offset two or more steps.

The indicating characters can be associated in a number of ways with the type bars. Probably the simplest way would be 30 to engrave or stamp the indicating numerals in the front ends of the type bars and to then fill in the depressions with coloring matter such as enamel to make 35 the characters plain. As shown in Fig. 3, leather facing disks 42 can be secured to the front ends of the type bars with the numerals printed thereon. This method has advantages for the soft leather or other material 40 will deaden the blow of the hammers against the type bars and will make the machine less noisy.

Instead of leather disks, caps 43 of thin metal, celluloid, or other suitable material 45 may be slipped over the front ends of the type bars with indicating numerals printed thereon. Such means will probably be used for applying indicating characters in machines already in use, it being then possible 50 to equip a machine for indication much in the same manner as finger caps are applied to set-up keys in adding machines or typewriting machines.

Instead of directly applying or securing 55 indicating numerals to the type bars, targets could be secured to the type sectors with numerals printed thereon to appear adjacent the type bar ends. For example, where there is sufficient space between the rows of 60 type bars target plates 44 of thin sheet metal can be secured to the type sectors with the numeral receiving target tongues 45 projecting into the space between the type bars as indicated in Figs. 5 and 6.

65 By means of my invention calculating ma-

chines of the type referred to can be readily transformed into machines in which the operator has a complete and accurate check before printing.

I do not, of course, desire to be limited 70 to the exact application and arrangement shown and described as modifications are no doubt possible which would still come within the scope of the invention.

I claim as follows:

1. In a machine of the class described, the combination of vertical rows of numeral type bars arranged in a horizontal row of decimal orders, means for shifting numeral rows to bring selected numeral bars into 80 a printing plane, said bars at one end having numeral printing characters and at their other ends having indicating characters associated therewith indicative of the numeral printing characters but offset therefrom to appear in an indicating plane offset from the printing plane when the numeral rows are shifted.

2. In a machine of the class described, the combination of vertical rows of numeral type bars arranged in a horizontal row of decimal orders, means for shifting numeral rows to bring selected numeral bars into a printing plane, said bars at one end having numeral printing characters, and 90 numerals applied to the other ends of the bars but offset numerically to be arranged in an offset plane of sight in accordance with the numeral printing characters on the bars in the printing plane.

3. In a calculating machine, the combination of a type sector, type bars arranged in a vertical row on said sector and adapted for transverse shifting thereon, a type roller, means for shifting said sector in 105 front of the roller to bring a selected type bar into the printing plane, printing numerals on the inner ends of said type bars, and indicating numerals at the front ends of the type bars offset numerically whereby 110 when one of said bars is in the printing plane its numeral will appear at the front of another bar in an indicating plane away from the printing plane.

4. In a calculating machine, the combination of a plurality of type sectors, numeral printing bars arranged in a vertical row on each sector, a printing roll, a keyboard and mechanism for selecting sectors for predetermined movement, means for 120 shifting selected sectors into position in front of the type roller to bring the corresponding type bars into the printing plane, the inner ends of the type bars of each row having printing numerals thereon and the 125 front ends of such bars having indicating numerals associated therewith but offset numerically, such numerical offset being the same on each sector, whereby when sectors have been shifted to bring the correspond- 130

ing bars into the printing plane the printing numerals on such bars will be represented by the corresponding offset indicating numerals in an indicating plane offset 5 from the printing plane.

5. In a calculating machine of the class described, the combination of a horizontal row of type sectors, numeral printing bars arranged in a vertical row on each sector 10 and shiftable horizontally, printing numerals zero to nine on the rear ends of the printing bars of each row, a row of indicating numerals zero to nine associated with the front ends of each printing numeral 15 row, the indicating numeral rows being offset vertically to extend a distance above the printing numeral rows, those indicating

numerals in the offset ends of the rows being carried by the sector frames while the other indicating numerals of each row 20 are applied respectively to the fronts of the printing bars, and means for selectively raising sectors to bring corresponding printing bars into a printing plane, the corresponding indicating numerals being then 25 arranged in an indicating plane above the printing plane to indicate to the operator the built-up number to be printed by the bars in the printing plane.

In witness whereof I hereunto subscribe 30 my name this 17th day of November, A. D., 1916.

PHILIP N. SEA.
